[57] CLAIM

The ornamental design for a commando armored patrol car, as shown and described.

DESCRIPTION

FIG. 1 is a left side elevational view of a commando armored patrol car showing my new design, the right side being substantially a mirror image thereof;

FIG. 2 is a rear elevational view thereof;

FIG. 3 is a top plan view thereof with the gun and mounting assembly in an alternate position; and

FIG. 4 is a front elevational view thereof.
